LAUNCHING DEVICES

Gunther M. Richter, R.F.D. 1, Brookfield, Conn.
Filed Aug. 12, 1960, Ser. No. 49,342
2 Claims. (Cl. 124—13)

This invention relates to amusement apparatus and, more particularly, to a device for launching a projectile such as a toy rocket.

Many devices have heretofore been proposed for propelling miniature projectiles. However, each of these devices has been characterized by certain shortcomings. For example, one class of launching devices employs mechanical actuators such as springs for imparting the required force to a projectile. Devices such as this are unnecessarily complex and are subject to mechanical difficulties.

A second class of devices utilizes small explosive charges. The height to which projectiles will ascend when actuated by small charges is limited. More effective charges are dangerous to children and, in any event, are difficult to obtain.

A third class of devices, to which this invention belongs, includes those actuated by compressed air. A familiar type of launcher employs a compressed air chamber having a detachable head serving as a projectile, a hand operated piston, and a mechanical check valve. The piston is pumped until sufficient pressure is built up to launch the projectile. The primary drawback to such devices is the fact that the check valve is easily disabled—for example, by dirt entering the mechanism.

Another disadvantage of piston-operated devices generally is that the pistons are relatively short in comparison with their length of movement. This results in a poor air seal due to the short leakage distance between the compression chamber and the atmosphere. The short length also contributes to mechanical misalignment and distortion, especially when operated by small children lacking in a high degree of manual dexterity and coordination.

One device which attempts to remove the disadvantages of piston-type compressors employs a pair of telescopically associated tubes, the innermost tube having a detachable projectile on its outer end. This type of device is severely limited in the amount of compression obtainable as the smallest volume to which the air can be compressed is the volume of the inner tube. Such a device can seldom propel a projectile higher than approximately 25 feet.

A further disadvantage of all the foregoing devices is that they are constructed to be operable by both hands of the user. It is thus quite difficult for a child to control the direction in which the projectile is propelled as he normally lacks sufficient strength to keep the device pointed in the desired direction while simultaneously compressing the contained air.

It is, therefore, the primary object of the present invention to provide an improved launching device.

A further object is to provide such a device having no mechanical or explosive actuating members.

A further object is to provide such a device capable of propelling an object to greater heights than devices heretofore known.

A further object is to provide such a device capable of compressing the contained air to very small volumes.

A further object is to provide such a device having very few moving parts.

A further object is to provide such a device which is not subject to misalignment or distortion.

A further object is to provide such a device which can be easily kept aimed at a desired point in space during the compression stroke.

A further object is to provide such a device wherein

2

the leakage path between the compressed air and the atmosphere is quite long.

The above objects are achieved by providing an elongated tube open at both ends, an elongated piston longitudinally slideable within the tube, the nonengaged end of the piston being adapted to rest upon the ground during the launching operation, and a projectile detachably supported by the nonengaged end of the tube.

The manner in which this invention is constructed will be more apparent from the following detailed description taken with the figures of the attached drawing wherein:

FIG. 1 is a cross-sectional elevational view of the device in the telescoped position;

FIG. 2 is a cross-sectional elevational view of the device extended for the beginning of the compression stroke;

FIG. 3 is an elevational view showing the device partially telescoped and the projectile leaving the end; and

FIG. 4 is a cross-sectional plan taken along the line 4—4 of FIG. 3.

In the drawings, an inner tube 10 is closed at its upper end by a suitable stopper 12 to form a long compression piston. The lower end of tube 10 is closed by a cap 14 which circumferentially surrounds the lower portion of tube 10. An outer tube 16, open at both ends, fits snugly but slideably over tube 10. Tube 16 is surmounted by a detachable toy rocket having a hollow body portion 18 and guide fins 20.

In operation, the tubes are extended and the rocket 18 is placed over the upper end of tube 16. The lower end of tube 10 is placed against the ground to provide a firm base for aiming purposes. The extended launcher is aimed toward a point in space and the outer tube is moved rapidly downward over inner tube 10.

It has been found preferable to grasp the outer tube 16 together with rocket body 18 so as to prevent relative motion between the outer tube and rocket body during the compression stroke. In this way, extremely high pressures may be built up between stopper 12 and rocket 18.

When a suitable pressure has been attained, rocket body 18 may be released. An intriguing popping sound is made and the rocket soars rapidly to extreme heights.

As an example of this invention, a device of this type was constructed using heavy cardboard tubes. The inside diameter of the outer tube was 1 $\frac{5}{16}$ inches. The inner tube was 40 inches in length and the outer tube was 41 inches in length. Upon compression in the manner described, a light plastic rocket was propelled vertically upward approximately 100 feet. In order to rest upon the ground, it has been found desirable to make the inner tube at least 30 inches in length.

The provision of a hollow body in the rocket projectile is also useful in attaining greater heights. At the instant the rocket leaves the end of tube 16, body 18 is filled with compressed air. Expansion of this air from the tail of the rocket provides a jet propulsive thrust in addition to the initial launching force.

As a further help in attaining altitude, the ends of rocket fins 20 are bent in the manner shown in FIGS. 1—3. This causes the rocket to spiral in the manner of a projectile leaving a rifled barrel. A considerable increase in height has been found possible using this fin configuration.

The primary purpose of cap 14 is to provide a surface for supporting the launcher against the earth. Cap 14 also serves to protect the end of tube 10 from damage and, when in the form illustrated, the circumferential shoulder prevents tube 10 from being completely inserted in tube 16.

It will be understood that the device of this invention

may be made from any suitable material. More durable but more expensive devices could be constructed of metal or plastic tubes, for example.

I claim:

1. An amusement apparatus for launching a projectile which comprises: an elongated cylindrical outer tube open at both ends; elongated cylindrical tubular piston means having a first closed end, said first end being longitudinally slideable within said outer tube, substantially the entire cylindrical outer surface of said piston means being simultaneously engageable with substantially the entire inner surface of said outer tube, the non-engaged second end of said piston means being adapted to rest upon the ground during the launching operation; and a hollow substantially cylindrical projectile closed at its first end and open at its second end, said open end of said projectile

5

being adapted to fit the non-engaged end of said outer tube.

2. The apparatus of claim 1 wherein said piston has at its unengaged second end a circumferential shoulder on its outer surface.
